DRYING BOX AND INCUBATOR

Hans Brüning and Otto Schüller, Hanau, Germany, assignors to the firm of W. C. Heraeus, G. m. b. H., Hanau, Germany

Application September 28, 1935, Serial No. 42,632.
Renewed November 8, 1937. In Germany May 16, 1934

9 Claims. (Cl. 219—35)

The present invention relates to drying boxes and incubators which are automatically regulated to maintain, with extreme exactness, any adjustable heat degrees at uniform heat distribution, and particularly refers to the shape and the regulating devices of such apparatus.

Laboratory-drying boxes and incubators generally used hitherto have the form of a four-sided prism and as a rule are protected by asbestos sheets against heat losses.

As with devices of a cylindrical form the ratio between outer surface and volume is smaller than with a prismatic form, the heat losses for equal volumes are smaller. The insulation may easily be effected by vitreous insulating material or the like, having better heat insulating properties than asbestos sheets, because the cylindrical inner and outer walls of the apparatus are self-supporting. Whereas with boxes of prismatic form uniform distribution of temperatures offers serious difficulties, as the heating wires must be stretched upon tubes or frames arranged at the bottom, with a cylindrical form uniform heating of the space may easily be obtained by arranging, in a suitable manner, the heating wires in the form of small mica heating units around the cylindrical space. By arranging the heating elements near the door and at the lower half of the apparatus closer together than at other places and by using aluminium- or copper-sheet as material for the inner wall, uniformity of temperature of $\pm 1^\circ$ C. may easily be obtained within the whole space. The shelves or insertion plates are carried by a frame which may be removed by a simple operation, so that the inner wall of the box and all inner parts may easily be cleaned.

In the accompanying drawings, a construction according to the invention is shown by way of example.

Fig. 1 shows a front elevation of a drying box according to the invention, partly in cross section and partly broken away.

Fig. 2 shows a central longitudinal section through the device illustrated in Fig. 1.

Fig. 2a is a detail view.

Fig. 3 is a section on line 3—3 of Fig. 2.

Figs. 4 and 5 are diagrammatic cross sectional views showing two modified forms of construction of the invention.

Figs. 6 and 7 are diagrammatic illustrations of curves illustrating the action of the invention with respect to regulation.

The drying box or incubator shown in Figs. 1—3 rests upon a foot or support 1 and comprises an inner and an outer cylindrical wall of sheet metal

2 and 3 respectively both of which are closed by a bottom 4 and 5 respectively, preferably forming part of the corresponding wall. The inner cylindrical member 2 consists of sheet metal of high coefficient of thermal expansion, surrounds the useful space 6 of the apparatus and carries a series of mica heating units 7. The wall 2 is insulated against the outer wall 3 by vitreous insulating material 8 or the like. A door 9 hinged at 10 and insulated also by vitreous insulating material 11 or the like serves to close the apparatus. A frame 12, fitting the useful space 6, may easily be withdrawn and serves to carry plates 13 upon which material or the like to be treated may be arranged. In the lowest portion of the walls 2 and 3 an opening is provided and these openings are connected by a tube 14 through which liquid may be drained off in case a vessel breaks inside the apparatus. The tube 14 simultaneously serves to introduce air into the space 6. Diametrically opposite the tube 14 a similar tube 15 is provided also extending from the useful space 6 to the outside, where it opens into a socket 16 adapted to receive a thermometer 17 which extends into the useful space 6 and serves to indicate the temperature within the apparatus. In the cylindrical portion of the socket 16 openings 18 are provided through which damp air may escape to the atmosphere.

In drying boxes used hitherto the regulation of the temperature is effected by an inwardly projecting and exposed thermostat responsive to the temperature within the useful space and controlling a relay. In such regulating arrangements the heat is transferred from the heating elements to the wall of the useful space, from said wall to the air in the useful space and from the air to the feeler.

According to the invention, however, in cylindrical drying boxes the thermal expansion of the sheet metal member, surrounding the useful space, with regard to a rod of low coefficient of thermal expansion is used to regulate the temperature. As with the novel arrangement the wall of the useful space itself serves as regulating member, i. e., the path of heat transfer is considerably shortened, an extremely frequent action of the regulating device and thereby a temperature regulation of considerably higher precision results.

It is well known already to regulate electrical-heated tube stoves and heating plates by using the expansion of a portion of the wall, however, it is not known hitherto to use the thermal expansion of a portion of a wall with regard to a rod-shaped body, arranged outside the useful

space of drying boxes and incubators, to effect regulation of such devices, probably because inexactnesses were expected on account of bulgings of the thin walls and particularly on account of the fact, that no favored expansion of these walls occurs in any direction. Strong prejudices were to be cast off to use the known principle also in connection with drying boxes and incubators, because an exact or precise regulation was not to be foreseen. Thorough tests, however, have proved, that by using the known regulating principle in connection with drying boxes and incubators of a cylindrical shape, a considerably better and more precise regulation is obtained than has been possible hitherto with the use of immersed feelers. A further important advantage of the novel regulating device consists in this, that troubles are avoided which are caused by the action of corrosive gases upon the feeler or by bendings of the latter. The regulating device according to the novel arrangement is perfectly protected and lies entirely outside the useful space of the box or incubator. By omitting the usual feeler within the apparatus simultaneously the available space may be better utilized.

If, in cases in which a portion of the wall not directly heated is used for the regulation, the regulation of the temperature is to be further improved, the portion of the wall in question may be provided with an auxiliary heating coil, operating in accordance with the main heating coil. The improvement is based upon the idea to effect an earlier response of the regulating device than would be the case with heat transfer by heat conduction through the cover of the useful space and by air convection within the useful space. As has been shown by tests, during the switching off period in which the auxiliary heating coil is rendered currentless, complete compensation results between the temperature of the useful space and that of the wall, so that switching on of the current again is always effected at the same temperature. By shortening the heating period, the effect is obtained, that the regulator still more frequently operates than otherwise and therefore the regulating curve of the device is further improved.

The heating period may, by suitably proportioning the heating effect of the auxiliary heating, be shortened as desired. Of course, this shortening is not allowed to be carried on so far, i. e. the temperature of the regulator is not allowed to so strongly lead the temperature of the box or incubator, that the amount of heat, supplied during the heating period to the box or incubator, is, not sufficient to compensate for the idle losses at the adjusted temperature. It has been found, that the upper limit for the heating effect of the auxiliary heating lies at about 15% of the capacity of the supply mains.

If an auxiliary heating is to be provided on particularly thin walls of sheet metal such as a paper thin wall, such walls are preferably reinforced by a flat or profiled strip of the wall metal and the auxiliary heating coil is then arranged upon this strip. Preferably the strip simultaneously serves in such cases as expansion element for operating the regulating contact.

As may best be seen from Fig. 3, a U-shaped strip 28 of sheet metal, serving as reinforcement, is riveted or soldered to the bottom 4 of the apparatus which is not directly heated. In this U-shaped strip 28 auxiliary heating coils 21 and 22, connected to each other by a wire 23 and surrounding the rod 19, are arranged. The rod 19

of low coefficient of thermal expansion preferably is fixed at 24 to the strip 28 itself. The free ends of the auxiliary heating coils 21 and 22 are, by wires 25 and 26 respectively connected to the heating elements 7 which in turn are connected by wires 27 and 28 to contacts 29 and 30 (Figs. 2 and 2a), forming part of a heating circuit supplied with current by any suitable source of power not shown in the drawings. Other parts of the heating circuit, as switches, relays, control lamps and so on, are also not shown in the drawings, as they do not form part of the invention. The contacts 29 and 30 are carried by arms 31 and 32 respectively. The arm 32 may, by means of a spindle 33 provided with a knob 34, be adjusted with regard to the arm 31, thus pressing the contacts 29 and 30 more or less firmly together, depending on the temperature desired to be obtained within the space 6. The other arm 31, carrying the contact 29, is swingably arranged and connected to the free end of the rod 19.

When the drying box or incubator is heated, the rear wall or bottom 4 expands, whereas the rod 19 retains about its original length. At a certain temperature, the free end of the rod 19 disengages the contact 29 from the counter-contact 30, whereby the heating circuit is opened. Upon the now following cooling of the box, the bottom 4 contracts and the end of the rod 19 allows the contact 29 to again approach its counter-contact 30, until the contacts 29, 30 and thereby the heating circuit are closed again.

Fig. 4 diagrammatically shows another construction of the regulating arrangement. In this case also the wall 2 of the useful space 6 of the drying box consists of a metal of high coefficient of thermal expansion and is surrounded by a series of heating elements 7. Parallel to the longitudinal axis of the apparatus and between the cylindrical walls 2 and 3 a rod 19 is arranged which again consists of material of low coefficient of thermal expansion. One end 35 of the rod 19 is connected to the cylindrical wall 2 surrounding the useful space 6. The free end of the rod 19 extends through a hole in the arm 31 which is swingably arranged and carries the contact 29 connected to the heating circuit. The countercontact 30 cooperating with the contact 29, is carried by the arm 32 which, by means of the spindle 33 with knob 34, may be brought in predetermined positions, corresponding to the temperatures which are desired within the space 6.

The operation of this device is the same as described with reference to the apparatus shown in Figs. 1-3.

According to a further modification, a tube-like feeler 35 provided with an auxiliary heating coil 36 may, without connection with the wall 2 surrounding the useful space 6, be immersed into the interior of the box or incubator and be used for the fine regulation. The coil 36 is well isolated from the tube 35 and the rod 19 which it surrounds. The ends of the rod 19 are fixed to the closed end 37 of the tube 35 and to the arm 31 respectively. For the rest the regulating device corresponds in construction and operation to the already described devices, with the only difference, however, that in the apparatus, just described and shown in Fig. 5, it is the difference of the thermal expansion between the tube 35 and the rod 19 which is used to control the contacts 29 and 30. The additional heating which is known already for regulators consisting of bimetal, has, however, hitherto never been used.

in connection with expansion regulators comprising a rod.

The effect obtained by the regulation may be seen from the regulating curves diagrammatically indicated in Figs. 4 and 5. Fig. 4 shows the regulating curve of a box having the heating coil arranged at the outside and provided with a closed inner space into which immerses the feeler having no auxiliary heating coil. Fig. 5 shows the regulating curve of a box of equal construction in which the feeler is heated by an auxiliary heating coil. In both cases the heating- and cooling curves have the same inclination towards the abscissa, also the switching-on temperature is the same in both cases. The time of the switching periods, however, is differently long from which follows the higher exactness of regulation by the use of the additionally heated regulator.

What we claim is:

1. In an electrically heated receptacle for providing a chamber having a substantially constant temperature, the combination of a receptacle having a cylindrical side wall and having end walls, one of said end walls constituting a closure, said receptacle being constructed of metal having a high coefficient of thermal expansion, with an insulating covering for said receptacle and an enclosure for said insulating covering, electrical heating elements located outside said receptacle and inside said insulating covering, an element having a low coefficient of thermal expansion located outside said receptacle and having one end fixedly secured to said receptacle adjacent one edge of the cylindrical wall, a circuit maker and breaker for controlling said heating elements and carried by said receptacle at a point spaced from the fixed end of said element, and an operative mechanical connection between the other end of said element and said circuit maker and breaker whereby substantially uniform temperature is maintained in said receptacle, said receptacle having an auxiliary heating coil controlled by said circuit maker and breaker and arranged primarily for heating that part of the receptacle between the points of attachment of said element and of said circuit maker and breaker, whereby the time lag in the action of the circuit maker and breaker responsive to changes in temperature is diminished.

2. In an electrically heated receptacle for providing a chamber having a substantially constant temperature, the combination of a receptacle having a cylindrical side wall and having end walls, one of said end walls constituting a closure, said receptacle being constructed of metal having a high coefficient of thermal expansion, with an insulating covering for said receptacle and an enclosure for said insulating covering, electrical heating elements located outside said receptacle and inside said insulating covering, an element having a low coefficient of thermal expansion located outside said receptacle and having one end fixedly secured to said receptacle adjacent one edge of the cylindrical wall, a circuit maker and breaker for controlling said heating elements and carried by said receptacle at a point spaced from the fixed end of said element, and an operative mechanical connection between the other end of said element and said circuit maker and breaker whereby substantially uniform temperature is maintained in said receptacle, said element extending diametrically across one end wall of said receptacle and said receptacle having an auxiliary heating coil controlled by said circuit maker and breaker and arranged primarily

for heating that part of the receptacle between the points of attachment of said element and of said circuit maker and breaker, whereby the time lag in the action of the circuit maker and breaker responsive to changes in temperature is diminished.

3. A device as claimed in claim 1 in which said circuit maker and breaker has means for continuously adjusting the point of actuation of said circuit maker and breaker whereby any operating temperature may be selected and maintained within a predetermined range of temperatures.

4. In an electrically heated receptacle for providing a chamber having a substantially constant temperature, the combination of a receptacle having a cylindrical side wall and having end walls, one of said end walls constituting a closure, said receptacle being constructed of metal having a high coefficient of thermal expansion, with an insulating covering for said receptacle and an enclosure for said insulating covering, electrical heating elements located inside said insulating covering, an element having a low coefficient of thermal expansion carried by said receptacle and having one end fixedly secured to said receptacle adjacent one edge of the cylindrical wall, a circuit maker and breaker having a movable contact carrying arm for controlling said heating elements and carried by said receptacle at a point spaced from the fixed end of said element, and an operative mechanical connection between the other end of said element and said circuit maker and breaker whereby substantially uniform temperature is maintained in said receptacle, said element having a direct mechanical engagement with said arm to eliminate backlash in the actuation of said circuit maker and breaker.

5. A device as claimed in claim 4 in which said element slidably engages said arm and said element has a shoulder for actuating said arm.

6. In an electrically heated receptacle for providing a chamber having a substantially constant temperature, the combination of a support with a receptacle having a cylindrical side wall and having end walls, said receptacle having its axis extending substantially horizontally and one of said end walls constituting a closure, said receptacle being constructed of metal having a high coefficient of thermal expansion, with an insulating covering for said receptacle and an enclosure for said insulating covering, electrical heating elements located outside said receptacle and inside said insulating covering, an element having a low coefficient of thermal expansion located outside said receptacle and having one end fixedly secured to said receptacle adjacent one edge of the cylindrical wall, a circuit maker and breaker for controlling said heating elements and carried by said receptacle at a point spaced from the fixed end of said element, and an operative mechanical connection between the other end of said element and said circuit maker and breaker whereby substantially uniform temperature is maintained in said receptacle, said circuit maker and breaker being located outside said insulation and said element extending through said insulation to said circuit maker and breaker.

7. A device as claimed in claim 4 in which the end wall of said receptacle between said fixed end of said element and said circuit maker and breaker is reinforced with a member having substantially the same coefficient of thermal expansion as said receptacle.

8. In an electrically heated receptacle for providing a chamber having a substantially constant

temperature, the combination of a receptacle having side walls and having end-walls, one of said walls constituting a closure, said receptacle being constructed of metal having a high coefficient of thermal expansion, with an insulating covering for said receptacle and an enclosure for said insulating covering, electrical heating elements located inside said insulating covering, an element having a low coefficient of thermal expansion carried by said receptacle and having one end fixedly secured to said receptacle adjacent one edge of an outer wall, a circuit maker and breaker having a movable contact carrying arm for controlling said heating elements and carried by said receptacle at a point spaced from the fixed end of said element, and an operative mechanical con-

nexion between the other end of said element and said circuit maker and breaker whereby substantially uniform temperature is maintained in said receptacle, said element having a direct mechanical engagement with said arm to eliminate backlash in the actuation of said circuit maker and breaker. 5

9. A device as claimed in claim 8 in which said circuit maker and breaker has means for continuously adjusting the point of actuation of said 10 circuit maker and breaker whereby any operating temperature may be selected and maintained within a predetermined range of temperatures.
